UNITED STATES PATENT OFFICE.

HENRY B. MORRIS, OF MICHIGAN CITY, INDIANA.

DESIGN FOR CANE FABRIC.

SPECIFICATION forming part of Design No. 26,875, dated April 6, 1897.

Application filed February 18, 1897. Serial No. 624,054. Term of patent 7 years.

To all whom it may concern:

Be it known that I, HENRY B. MORRIS, a citizen of the United States, residing in Michigan City, in the county of La Porte and State of Indiana, have invented and produced a new and original Design for Cane Fabrics, of which the following is a specification, and which is illustrated in the accompanying drawing, showing a face view of a small piece of fabric with my design applied.

Cane fabric containing my design has alternate close-woven and open-mesh stripes A and B of substantially the same width.

Each stripe A is made up of a series of parallel strips *a*, arranged close together and divided up into short lengths or sections *a'* by a series of cross-strips *a''*.

Each stripe B has a series of strips *b*, which

form continuations of the cross-strips *a''*, and a series of diagonally-arranged strips *b'*, which 20 form with the strips *b* a series of hexagonal figures *x*.

The leading feature of my design is the alternately-arranged close-woven and open-mesh stripes of substantially the same width, 25 the latter of which each contains a series of hexagonal figures.

I claim—

The design for cane fabric substantially as herein shown and described. 30

In testimony whereof I have hereunto subscribed my name.

HENRY B. MORRIS.
